Primary Examiner — Rebecca Tsehay(74) Attorney, Agent, or Firm — Adibi IP Group, PC;
Amir V. Adibi; Andrew C. Palmer(57) CLAIM

The ornamental design for a portable scent dispensing ashtray, as shown and described.

DESCRIPTION

FIG. 1 is a perspective view of a portable scent dispensing ashtray showing my new design.

FIG. 2 is a front view showing my new design.

FIG. 3 is a left side view thereof.

FIG. 4 is a right side view thereof.

FIG. 5 is a top view thereof; and,

FIG. 6 is a bottom view thereof.

The broken lines in the drawings depict portions of the portable scent dispensing ashtray that form no part of the claimed design. The broken lines in FIG. 2 is environmental subject matter only and form no part of the claimed design. The broken lines in FIG. 3 illustrate a cigarette in broken line is environmental subject matter only and form no part of the claim designed.
